MULTIPLE PATTERN GRADER

Angelo Di Mino, Rochester, N. Y.

Application July 5, 1955, Serial No. 519,916

6 Claims. (Cl. 33—12)

This invention relates to a machine for duplicating a garment pattern in different sizes from the original, or master pattern.

An object of this invention is to provide a machine whereby a plurality of workable patterns for use in producing garments may be formed from a single master pattern, but of sizes larger and smaller than the original master pattern.

Another object of this invention is to provide a machine for producing patterns for garments whereby the patterns can be produced from a master or original pattern in a greatly reduced period of time, so that the reproduced patterns will be produced at a relatively small cost.

It is well known that in producing garments from patterns, a number of pattern pieces are required and where an original pattern is produced, duplicate patterns have heretofore been made in sizes larger or smaller than the original pattern by cutting around the original pattern at predetermined distances away from the edges of the original pattern. This procedure, however, requires a considerable time period, and it has always been a problem to hold the blank or new sheets firm during the cutting process.

It is, therefore, an object of this invention to provide a machine which will firmly hold the master or original pattern and will also permit adjustment and firm holding of the blank sheets so that they can be cut with the master pattern as a guide.

With the foregoing and other objects in view which will appear as the description proceeds, the invention consists of certain novel details of construction and combinations of parts, hereinafter more fully described and pointed out in the claims, it being understood that changes may be made in the construction and arrangement of parts without departing from the spirit of the invention as claimed.

In the drawings:

Figure 1 is a plan view of a machine constructed according to an embodiment of this invention, showing the machine in original starting position.

Figure 2 is a plan view of the machine showing the first adjustment of the machine for the first pattern cut.

Figure 3 is a plan view of the machine showing the adjustment thereof for making the second pattern cut.

Figure 4 is a plan view of the machine showing the adjustment thereof for making the third pattern cut.

Figure 5 is a plan view of the machine showing the adjustment thereof for making the fourth pattern cut.

Figure 6 is a plan view of the machine showing the adjustment thereof after the patterns have been completely cut and the machine returned to its original starting position.

Figure 7 is an end elevation of the machine.

Figure 8 is a horizontal section of the machine.

Figure 9 is a vertical sectional view taken on the line 9—9 of Figure 8.

2

Figure 10 is a fragmentary vertical sectional view taken on the line 10—10 of Figure 9.

Figure 11 is a fragmentary vertical sectional view taken on the line 11—11 of Figure 9.

5 Figure 12 is a fragmentary vertical sectional view taken on the line 12—12 of Figure 9.

Figure 13 is a fragmentary vertical sectional view taken on the line 13—13 of Figure 9.

10 Figure 14 is a fragmentary vertical sectional view taken on the line 14—14 of Figure 9.

Figure 15 is a fragmentary vertical sectional view taken on the line 15—15 of Figure 8.

Figure 16 is a fragmentary vertical sectional view taken on the line 16—16 of Figure 8.

15 Referring to the drawings, and first to Figures 7 to 15 inclusive, the numeral 20 designates generally a base plate having the housing 21 mounted thereon. The housing 21 is formed of opposite side walls 22 and 23, a top wall 24 and a rear end wall 25. The housing 21 has 20 rotatably disposed between the end walls 22 and 23 upper and lower gear shafts 26 and 27 respectively. The upper shaft 26 has a hand wheel or operator 28 secured to one end thereof whereby shaft 26 may be manually rotated. Shaft 27 is journaled between end walls 22 and 23 and is rotated, as will be hereinafter described.

Shaft 26 has fixed thereon a spur gear 28' which meshes with a smaller spur gear 29 fixed on shaft 27. In this manner, shaft 27 is rotated at a speed greater than shaft 26 and in the present instance, the gear ratio is substantially two to one between gears 28' and 29.

30 A pair of cylindrical slide members 30 are disposed on the upper shaft 26 and are connected together in spaced relation by means of a U-shaped connecting bar 31. Each slide member 30 also has fixed thereon a right angularly disposed guide sleeve 32 within which an elongated gear rack 33 slidably engages. The gear rack 33 engages over the top of the gear shaft 26 and meshes therewith.

35 The lower shaft 27 has slidable thereon a pair of cylindrical slide members 34 which are connected together by means of a U-shaped connecting bar 35. The lower slide members 34 also have fixed thereto right angularly disposed guides 36 in which elongated gear racks 37 slidably engage. The racks 37 engage the lower side of gear shaft 27 and are movable right angularly relative to the latter. The upper shaft 26 has loosely or slidably mounted thereon an elongated sleeve 38, which has fixed 40 adjacent the outer ends thereof a pair of right angularly disposed rack guiding sleeves 40. These sleeves 40 are disposed on the lower side of sleeve 38 so that the racks 41 engaging the sleeves 40 will engage the lower side of shaft 26.

45 A lower inner pair of sleeves 42 are loosely disposed on lower shaft 27 and are connected together by means of a connecting rack bar 43. The sleeves 42 have fixed on the upper sides thereof rack guiding members 44 in which racks 45 slidably engage. The racks 45 slidably engage the upper side of lower shaft 27. The outer ends of each rack bar have secured thereto a paper clamping member generally indicated at 50.

55 Each clamping member 46, as shown in Figure 16, is formed of a lower resilient flat bar 47 and an upper resilient flat bar 48. The bar 48 is provided on the lower side thereof with one or more prongs 49 which are engageable through an opening 50 formed in the lower bar 47. One or more blank sheets are adapted to be firmly clamped between the jaws or bars 47 and 48 so that the sheet or sheets will be adjustable longitudinally and vertically, as will be hereinafter described.

60 In order to provide for the longitudinal adjustment of the racks 33, 37, 41 and 45, I have provided a vertically disposed shaft 51 which is extended through the top wall

24 of housing 21 and is journaled at its lower end in bearing 52 carried by the base plate 20. Shaft 51 is provided at its upper end with a hand wheel 53 whereby shaft 51 may be manually adjusted. Shaft 51 has fixed thereon an upper small gear 54 and a lower large gear 55. Upper gear 54 meshes on the inner side thereof with an elongated gear rack 56 fixed to sleeve 38 and an outer gear rack 57 is fixed to connecting bar 31 and meshes with the outer side of gear 54. Lower gear 55 has meshing therewith a lower elongated gear rack 58, which is fixed between the lower sleeves 42.

An outer lower gear rack 59 is fixed to connecting member 35 and meshes with the outer side of gear 55. A pointer or adjustment indicator 60 is secured to upper gear rack 56 and movable longitudinally of housing 21. A second pointer 61 is connected with a gear rack 62 slidable in a housing 63 which is fixed to a sleeve 64. Sleeve 64 is loosely disposed on upper shaft 26 adjacent gear 28. Pointer 61 indicates the vertical adjustment of the blank sheets, whereas pointer 60 indicates the longitudinal adjustment of the blank sheets.

A master pattern or templet 65 is firmly held in spaced relation relative to the base 20 by means of a clamping member 66. The master pattern or templet 65 is adapted to overlie a series of blank sheets which are clamped in the clamping jaws 47 and 48. The clamping jaws carried by the rack bars 37 are the lowermost jaws, whereas the clamping bars carried by the rack bars 45 are the upper or top clamping bars. The clamping bars or jaws carried by rack bars 41 are the jaws immediately below the top bars 45, and the clamping jaws or bars carried by rack bars 35 are next to the bottom clamping jaws.

In the use and operation of this machine, a series of blank sheets of initially rectangular configuration are disposed in superposed relation and are substantially larger in size than the master pattern or templet 65. The indicators 60 and 61 are initially disposed at zero position when the blank sheets are secured in the clamping members 46. The pairs of rack bars are then adjusted longitudinally by turning wheel 53 clockwise to shift pointer 60 substantially 1°. With adjustment of wheel 53, gear 55 will move rack 58 to the right and rack 59 to the left. At the same time rack 56 will move to the right and rack 57 to the left. Due to the smaller diameter of gear 54 as compared to gear 55, the gear racks 56 and 57 will be moved in opposite directions a shorter distance than racks 58 and 59 are moved by gear 55. Hand wheel 28 is then adjusted counterclockwise to move pointer 61 downwardly 1°. When hand wheel 28 is turned counterclockwise the gear racks 37 and 45 will be moved in opposite directions at right angles to the racks 56, 57, 58, and 59. As racks 37 and 45 are moved by rotation of toothed shaft 27, shaft 26 will move racks 33 and 41 in opposite directions for a lesser distance than the movement of racks 56 to 59. The templet 65 remains stationary, and when the several pairs of rack bars with clamps are adjusted as shown in Figure 2, the blank sheets will be shifted after the manner shown in Figure 2. A first cut is made, as indicated at 67, in the shifted blank sheets. A second cut is then made in the blank sheets after the blank sheets have been shifted as shown in Figure 3. The second shifting of the blank sheets is made by adjusting hand wheel 28 an additional space downwardly, while hand wheel 53 remains stationary. The second cutting is then made along the templet line 68.

A third cut 69 is then made in the blank sheets after these sheets have been adjusted to the positions shown in Figure 4. This adjustment is made by a horizontal adjustment and turning of wheel 53 to shift pointer 60 to the right two spaces. Hand wheel 28 at this time remains stationary. A fourth cut 70 is made in the blank sheets after the blank sheets have been shifted to the positions shown in Figure 5. At this time, pointer 60

is to the left of zero position, and pointer 61 is in the same position as shown in Figure 3.

If the pattern is to be varied as to the length of the garment, a fifth cut is made along the line 71 after a further longitudinal adjustment of the blank sheets.

When the now cut blank sheets are returned to their original positions, these blank sheets, which are now pattern sheets, will be disposed as shown in Figure 6 with two of these sheets larger than the templet or master 65 and two of the original blank sheets smaller than the templet.

As an example, the templet may be of size 34, and the additional pattern sheets will be of sizes 30, 32, 36 and 38. It will of course be understood that intermediate sizes may also be obtained by variation in adjustment of the blank sheets relative to the master or templet. Each blank sheet will be firmly held laterally of the center thereof by the pair of clamping members 46, so that the blank sheets cannot shift after being adjusted.

With a machine as hereinbefore described, any number of patterns may be formed from an initial master pattern, and the forming of these additional patterns can be made quickly, so that these additional patterns will be made at a relatively small cost. Where the additional patterns are designed for garments which are to be made larger only above the waist or body portion, without enlargement as to length, these patterns can be easily formed by eliminating one or more steps hereinbefore described.

Having thus described the invention, what is claimed is:

1. A pattern machine comprising a housing, a templet clamping means fixed to and extending from said housing, a plurality of blank sheet clamping members, means connecting said members in pairs, means adjusting said members longitudinally of said housing, and means adjusting said members vertically of said housing.

2. A pattern machine comprising a housing, a templet clamping means fixed to and extending from said housing, a plurality of blank sheet clamping members, means connecting said members in pairs, and means adjusting said pairs of clamping members relative to each other.

3. A pattern machine comprising a housing, a templet clamping means fixed to and extending from said housing, a plurality of blank sheet clamping members, means connecting said members in pairs, means adjusting certain ones of said pairs of clamping members in one direction, and means adjusting certain others of said clamping members in a direction at right angles to said one direction.

4. A pattern machine comprising a housing, a templet clamping means fixed to and extending from said housing, a plurality of blank sheet clamping members, means connecting said members in pairs, and means adjusting certain ones of said pairs of clamping members in one direction while simultaneously adjusting certain others of said clamping members in the opposite direction.

5. A pattern machine comprising a housing, a templet clamping means fixed to and extending from said housing, a plurality of blank sheet clamping members, means connecting said members in pairs, means adjusting adjacent pairs of clamping members in one direction while simultaneously adjusting the remaining adjacent pairs of clamping members in the opposite direction.

6. A pattern machine comprising means firmly securing a templet in fixed position, means holding a plurality of superposed blank sheets beneath said templet, and means adjusting said blank sheets relative to said templet and to each other.
